UNITED STATES PATENT OFFICE.

THOMAS McNICKLE PARK, OF LAKE BOLAC, VICTORIA, AUSTRALIA.

FEEDING APPARATUS FOR THRASHING MACHINES.

1,415,046.

Specification of Letters Patent.

Patented May 9, 1922.

Application filed March 12, 1920. Serial No. 365,303.

To all whom it may concern:

Be it known that I, THOMAS McNICKLE PARK, a subject of the King of Great Britain and Ireland, and a resident of the post town of Lake Bolac, in the shire of Ararat, county of Rippon, State of Victoria, Commonwealth of Australia, (whose post-office address is Lake Bolac, in the said shire of Ararat,) have invented a certain new and useful Improved Feeding Apparatus for Thrashing Machines, of which the following is a specification.

This invention relates to thrashing machine feeding apparatus of the kind wherein the material to be thrashed is conveyed from a hay stack or the like, placed upon a feed belt and conveyed to the machine without distinction being made between different classes of material so far as the manner of feeding is concerned. Experience shows that light material and tough material, for example, should not be fed alike to the thrasher and that it is very desirable in some instances to feed the heads of grain ahead of their stalks or hay, and in other instances to feed the whole laterally, and that by varying the manner of feeding or direction of delivery better results are obtained in thrashing.

The object of this invention is to provide apparatus whereby material may be conveyed from any stack or position around the machine and whereby any desired variation in the direction of feeding to the thrashing machine may be effected, thereby obtaining better results without calling for undue manual labor or skill. The invention, further, may be easily applied to existing thrashing machines, is comparatively cheap to manufacture, and does not require constant attention.

Referring to the drawings which form part of this specification:—

Figure 1 is a side elevation of the feeding apparatus the turn-table and conveyor and subsidiary parts being omitted for convenience of illustration.

Figure 2 is a plan of the invention, parts being omitted and broken away for convenience of illustration.

Figure 3 is an end view looking in the direction of the arrow Figure 1, parts being omitted and broken away for convenience of illustration.

Figure 4 is a perspective detail view of a 55 centre sliding bearing.

Figure 5 is an enlarged detail view showing the manner of securing a tine to an oscillating shaft.

Figure 6 is a plan of Figure 5.

Figure 7 is a side elevation of Figure 2, parts being omitted and broken away for convenience of illustration.

The invention includes a casing having a right side 2 and a left side 3. Extending between the sides is a bottom 4 inclined from the front downwardly towards the back of the casing. The casing is disposed above, or over, or within the feed hopper of a thrashing machine. Above the casing is a stationary supporting ring or table preferably of angle section comprising a flat or horizontal portion 5 and an upstanding flange or collar 6 formed on the inner periphery of the horizontal portion. Resting upon the flat or horizontal portion 5 is a ring or turntable of similar section to the stationary table and having a flat horizontal portion 7 and an upstanding collar 8. The turntable is retained in position by suitable 80 tongues or the like 9 projecting outwardly from the upstanding collar 6.

The turntable carries a series of anti-friction rollers 11 whereby the turntable may be easily rotated by hand to bring the conveyor, hereinafter referred to, into any desired position in which it may be locked by a locking pin or pins 12 passing through locking pin holes in the horizontal or flat portions 5 and 7 of the turntable and supporting table.

Carried by the turntable or extensions therefrom is a main conveyor shaft 13 to which is pivoted the inner end of a conveyor trough 14. This is of any desired 95 length and extends outwardly from the turntable. The conveyor shaft 13 may be driven in any suitable manner, but preferably is provided with a belt pulley 15 at each of its ends. Located within the trough is an end- 100 less conveyor band 16 which passes around a roller or pulley 17 upon the intermediate portion of the conveyor shaft 13 and also around an idle roller 18 located at the outer end of the trough 14. Any suitable means 105 may be provided for raising and lowering the outer end of the trough and locking it in any desired position.

Figure 4 is a perspective detail view of a 55 centre sliding bearing.

Such means may comprise a yoke 19, the lower ends of the legs of which are pivoted to a pin 20 carried by the turntable or extensions therefrom. A limit stop 21 is carried by the trough 14 to limit the fall of the yoke. Mounted in the upper end of the yoke 19 is a pulley 22 over which passes a line 23, one end of which is secured to the trough 14 and the other end of which is secured to a drum 24 secured upon a shaft 25 mounted in suitable bearings carried by the turntable. Secured upon the shaft 25 is also a worm wheel 26 engaged by a hand operated worm 27. The stop 21 may be dispensed with and a removable stay be disposed between the top of the yoke and any suitable part of the turntable.

Mounted in suitable bearings disposed at the front of the casing is a lateral shaft 30 having a driving pulley 31. Disposed upon the right hand end of said shaft are inner and outer right sliding toothed wheels 32-33 united by a collar 34. Engaging the collar 34 is a fork 35 operated by a suitable lever. Mounted upon the left end of the driving shaft 30 are inner and outer left sliding toothed wheels 36-37 united by a collar 38. Engaging the collar 38 is a fork 39 controlled by a suitable lever. Loosely mounted upon the shaft 30 are bevel wheels 90-91, each of which may be utilized to rotate a belt pulley 92. Engaging the bevel wheels 90-91 is a third bevel wheel 93 connected to rotate a belt pulley 94. Slidably mounted upon the shaft 30 is a clutch sleeve 95 adapted to engage either of the wheels 90-91. When the conveyor is at right angles to the feed belts hereinafter described, which position has been shown for convenience in the drawings, the sleeve 95 by engagement with the correct bevel wheel 90 or 91 causes the pulley 94, by a suitable belt, to rotate the corresponding pulley 15 in the required direction.

When the conveyor is at right angles to the position shown in the drawings or parallel with the feed belts hereinafter described, the corresponding pulley 15 is rotated by a belt driven by one of the pulleys 92, the belt being crossed when necessary to maintain the travel of the conveyor in the correct direction. By universally mounting the pulley 94 to swivel in any direction the pulleys 92 may be dispensed with.

Mounted in suitable bearings and laterally disposed across the front of the casing behind the shaft 30 are right and left hand shafts 41 and 42. Secured to the outer end of the right shaft 41 are inner and outer toothed wheels 43-44. Secured to the outer end of the left shaft 42 are inner and outer toothed wheels 45-46. Carried by the right shaft 41 is a front right drum 47. Carried by the left shaft 42 is a front left drum 48. Passing around the front right drum 47 is a right

feed belt 49, the lower end of which passes around a rear right drum 50 mounted upon a right idle shaft 51. Passing around the front left drum 48 is a left feed belt 52 the lower end of which passes around a rear left drum 53 mounted upon a left idle shaft 54.

Mounted upon the outer end of the right hand shaft 41 is a right eccentric 55 having a strap 56 secured to one end of a connecting rod 57. The other end of the connecting rod by a pivot pin 58 is pivoted to the lower end of an arm 59 the upper end of which is secured to the outer end of a right oscillating shaft 60. The outer end of the right oscillating shaft 60 is mounted in a right sliding bearing 62. The inner end of the right oscillating shaft 60 is mounted in the right end of a centre sliding bearing 63. Mounted upon the outer end of the left hand shaft 42 is a left eccentric 64 having a strap 65 secured to one end of a connecting rod 66 the other end of which by a pivot pin 67 is pivoted to the lower end of an arm 68. The upper end of the arm 68 is secured to the outer end of a left oscillating shaft 69. The outer end of the left oscillating shaft 69 is mounted in a left sliding bearing 70. The inner end of the left oscillating shaft 69 bears in the left end of the centre bearing 63 before mentioned.

Outstanding from each of the right, centre and left sliding bearings 62, 63, 70 is a guiding rib 72. The rib of each bearing moves in a slot 73 formed in an inclined slideway 100 74 carried by the casing. Pivoted to the oscillating shafts 60-69 or the sliding bearings thereof are the lower ends of a series of links 75, the upper ends of which are pivoted to a lateral pivot bar 76. Pivoted to the lateral pivot bar 76 are the upper ends of a series of arms 77 the lower ends of which are secured to a rocking shaft 78 mounted in suitable bearings carried by the back 79 of the casing.

Secured to one end of the rocking shaft 78 is the inner end of a hand lever 81 having at its outer end a pivoted finger lever 82 connected to an operating wire 83 adapted to operate a spring controlled pawl 84 engaging a racked quadrant 85 carried by the casing.

Secured to each oscillating shaft 60-69 is a series of U shaped straps 86. Each U shaped strap 86 embraces the upper end of a tine 87. Passing through each U shaped strap 86 and the tine 87 thereof is a holding bolt 88.

With this invention the conveyor trough 14 is first elevated to the desired altitude and the sheaves of hay thrown from the stack 125 onto the conveyor band 16 by which they are carried along and dropped or delivered upon the feed belts 49-52. Any binding bands around the sheaves may be cut in any suitable manner. By operating the forks 35-39 the 130

sliding toothed wheels associated with either belt may be manipulated whereby one belt may be caused to travel at a faster speed than the other. As the driving shaft 30 rotates the toothed wheels thereon rotate the toothed wheels of the shafts 41-42 thereby rotating the drum upon each latter shaft and causing the belts 49-52 to move towards the tines 87 of the apparatus. As the shafts 41, 42 rotate, the eccentrics thereon cause the oscillating shafts to operate thereby rocking the tines to and fro above the belts. An even feed is thereby maintained. Should one belt be travelling faster than the other it is obvious that the end of the material upon that belt will be delivered to the thrashing machine ahead of that portion of the material resting upon the other belt. By this means the heads of material may be delivered ahead of the stalks or vice versa. If both belts travel at the same speed the material will be delivered evenly. The distance between the lower ends of the tines and the feed belts may be regulated by operating the hand lever 81 in relation to the racked quadrant 85. The rocking shaft 78 thereby causes the lateral pivot bar 76 through the links 75 pivoted thereto, to raise or lower the sliding bearings 62-63-70 in their slideways 74. The quantity of material fed is thereby regulated.

As the height of a stack diminishes, the outer end of the conveyor trough may be lowered by turning the shaft 25 and drum 24 or in any other suitable manner so that the said outer end is always conveniently situated to the operators. The conveyor may also be moved into any desired circumferential position by rotating the turntable and then locking the same by the pins 12. The conveyor belt 16 may be driven by the belt pulleys and gearing described or in any other suitable manner.

The whole apparatus may be conveniently mounted upon a thrashing machine or other portable apparatus and moved from place to place therewith.

Having now described my invention what I claim as new and desire to secure by Letters Patent is:—

1. Feeding apparatus for thrashing machines, comprising a turntable; a conveyor carried by the turntable to move bodily therewith; a plurality of delivery belts arranged side by side beneath the turntable and movable in the same direction to receive the material from the conveyor and discharge it at substantially the same point; and means for individually varying the speed of each belt.

2. Feeding apparatus for thrashing machines, comprising a movable support; a conveyor carried by said support to move bodily therewith; a plurality of delivery belts arranged side by side beneath said sup-

port and movable in the same direction to receive the material from the conveyor and discharge it at substantially the same point; and means for individually varying the speed of each belt. 70

3. Feeding apparatus for thrashing machines, comprising a support; a conveyor carried thereby; a plurality of delivery belts arranged side by side beneath said support and movable in the same direction to receive the material from the conveyor and discharge it at substantially the same point; a drive shaft; individual gear connections between said shaft and each belt, each gear connection including a change-speed device 80 and an operating device for each change-speed device to individually vary the speed of each belt.

4. Feeding apparatus for thrashing machines, comprising a turntable having an open central portion; a conveyor having its discharge end mounted on the rim of the turntable to move therewith, said end overhanging the open portion of said turntable to discharge the material therethrough; a plurality of delivery belts arranged side by side beneath the turntable to receive the material discharged from the conveyor, said belts moving in the same direction so as to discharge the material at substantially the same point; and means for individually varying the speed of each belt.

5. Feeding apparatus for thrashing machines, comprising a turntable having an open central portion; a conveyor having its discharge end mounted on the rim of the turntable to move therewith, said end overhanging the open portion of said turntable to discharge the material therethrough; a plurality of delivery belts arranged side by side beneath the turntable to receive the material discharged from the conveyor; said belts moving in the same direction so as to discharge the material at substantially the same point; a drive shaft; individual gear connections between said shaft and each belt; each gear connection including a change-speed device; and an operating device for each change-speed device to individually vary the speed of each belt. 110

6. Feeding apparatus for thrashing machines, comprising a turntable; a conveyor carried by the turntable to move therewith; a plurality of delivery belts arranged side by side beneath the turntable and movable in the same direction to receive the material from the conveyor and discharge it at substantially the same point; a set of tines arranged above each belt; means for individually varying the speed of each belt; and means for individually oscillating each set of tines accordantly with the speed of the corresponding belt. 120

7. Feeding apparatus for thrashing machines, comprising a turntable; a conveyor 130

1
carried by the turntable to move therewith; a plurality of delivery belts arranged side by side beneath the turntable and movable in the same direction to receive the material 5 from the conveyor and discharge it at substantially the same point; a set of tines arranged above each belt; driving means individual to each belt; and connections between each driving means and the corresponding set of tines for oscillating the latter.

8. In an improved feeding apparatus for thrashing machines, a turntable, means for locking the same in adjusted position, a conveyor trough carried by the turntable to turn therewith, a travelling conveyor band within the trough, a winding drum carried by the turntable, connections between the drums and the trough for elevating the outer 20 end of the trough when the drum is rotated, a plurality of travelling feed belts disposed below the turntable to receive the material discharged by the conveyor, a change speed gear associated with each belt, a plurality 25 of tines above the belts, means for oscillating the tines, and means for raising and lowering the tines.

9. In an improved feeding apparatus for thrashing machines, a plurality of travelling feed belts, means for varying the speed of each belt independently, a series of devices located above the belts for regulating the quantity of material fed by said belts, and means for adjusting the position of said devices in relation to the belt.

10. In an improved feeding apparatus for

thrashing machines, a casing, a plurality of feed belts moving therein, a change speed gear associated with each belt, an oscillating shaft carried by the casing and extending 40 across said belts, a plurality of depending tines carried by the shaft, a plurality of sliding bearings supporting the shaft, and a hand lever for adjusting the bearings to regulate the position of said shaft and tines 45 with relation to said belts and thereby control the quantity of material fed by the belts.

11. In an improved feeding apparatus for thrashing machines, a turntable, means for locking the same, a conveyor trough carried 50 by the turntable to turn therewith, a conveyor band within the trough, means for driving the band when disposed at different positions around the turntable, a casing below the turntable, a plurality of feed belts 55 moving through the casing in position to receive the material discharged by the conveyor, a variable speed gear controlling each belt, a plurality of sliding bearings mounted in the casing, a shaft mounted in the bearings and extending across said belts, means for oscillating the shaft, a plurality of tines carried by the shaft, a plurality of links associated with the oscillating shaft, a rocking shaft associated with the links to raise and 60 lower the tine-carrying shaft and a hand lever controlling the rocking shaft.

In testimony whereof I affix my signature.

THOMAS MCNICKLE PARK.

Witness:

H. A. NEVETT.
